UNITED STATES PATENT OFFICE.

CHARLES F. STODDARD, OF BOSTON, MASSACHUSETTS, ASSIGNOR TO
AMERICAN PNEUMATIC SERVICE COMPANY, OF DOVER, DELAWARE,
A CORPORATION OF DELAWARE.

PNEUMATIC-DESPATCH APPARATUS.

SPECIFICATION forming part of Letters Patent No. 783,151, dated February 21, 1905.

Application filed January 9, 1904. Serial No. 188,377.

To all whom it may concern:

Be it known that I, CHARLES F. STODDARD, of Boston, in the county of Suffolk and State of Massachusetts, have invented certain new and useful Improvements in Pneumatic-Despatch Apparatus, of which the following is a specification.

My invention relates to pneumatic-despatch apparatus, and especially to sending-terminals; and it consists of a cylinder open on one side and which contains a revolving drum chambered on opposite sides to receive the carriers. This drum on one side comes in line with the opening in the cylinder and on the opposite side in line with the transmission-tube, so that when a carrier is put into it from the open side of the cylinder and it revolves so that the chamber containing the carrier is brought opposite the transmission-tube the current of air flowing through the transmission-tube forces the carrier out of the chamber into the transmission-tube. The cylinder is provided with a table secured to it in such a way as to allow the carrier to roll into the revolving drum. This table is provided with a trip mechanism, so that when a carrier passes into the machine the operating mechanism is set in motion to move the revolving drum, so that the carrier is brought in line with the transmission-tube and discharges into the transmission-tube. The revolving drum is secured to a shaft which passes into a semicircular cylinder at one end and to which is secured a piston which revolves in this semicircular cylinder. In the transmission-tube, which is outside the sending-terminal, is placed mechanism consisting of a number of swinging vanes which operate a small valve controlling the lock on the operating mechanism of the main valve for the purpose of keeping the machine from operating while a carrier is in the chamber of the revolving drum, which is in line with the transmission-tube. As the carrier passes in front of this locking mechanism in the aforesaid tube and which is normally balanced by a pipe connected with the

aforesaid tube still farther away from the sending-terminal the pressure back of it, which is greater than that in front, unbalances the swinging vanes and operates an auxiliary valve, which in turn unlocks the machine, so that it may operate to despatch another carrier. In order that the full pressure of the transmission-tube shall not be thrown upon the carrier when it comes into line with the transmission-tube, I have provided a bypass around the sending-terminal which takes most of the pressure off of the carrier when it is brought into line with the transmission-tube, which does not allow the carrier to in any way stop the flow of air as it is coming into line with the transmission-tube.

The object of my invention is to produce a sending-terminal for pneumatic-despatch-tube systems which is effective in operation and simple in construction.

My invention consists of certain novel features hereinafter described, and particularly pointed out in the claims.

In the accompanying drawings, which illustrate a construction embodying my invention, Figures 1 and 2 are respectively side and rear elevations of the machine, showing the general arrangement of the parts. Fig. 3 is a plan view. Fig. 4 is a section on the line X-X, Fig. 1, through the main portion of the machine, showing the revolving drum and trip-finger. Fig. 5 is a section through the operating-cylinder of the machine to show the piston-controlling valve. Fig. 6 is a diagrammatic view of the trip mechanism and the safety-lock. Fig. 7 is a section through the operating-cylinder of the machine and piston with the parts in the opposite position to that shown in Fig. 5. Fig. 8 is a similar view to that shown in Fig. 4 with parts reversed. Fig. 9 is an enlarged detail view, partly in section, of the piston-controlling valve with the valve in the same position as shown in Fig. 5. Fig. 10 is a similar view to Fig. 6 with certain parts in reversed position. Fig. 11 is a cross-sectional view on the line X'-X', Fig. 2, omitting cer-

tain parts shown in Fig. 2 and showing the air-pressure entrance to the sending-terminal and the by-pass in section.

Like letters of reference refer to like parts throughout the several views.

The carrier is laid on the inclined table b' (shown best in Fig. 4) and rolls down into the chamber a^4 of the revolving drum a^5 , passing over the finger b^2 , and in doing so presses the finger b^2 down. When the carrier gets completely into the chamber a^4 , the finger b^2 returns to the position shown in Fig. 4. The finger b^2 is securely fastened to the shaft b^3 , at the other end of which is securely fastened the hammer-weight b^4 , Figs. 6 and 10. When the finger b^2 is pressed down by the carrier, the shaft b^3 is turned and the hammer-weight b^4 is raised away from the shaft b^5 . When the carrier is fully into the chamber a^4 , the finger b^2 is returned to its normal position by the weight of the hammer-weight b^4 . When the hammer-weight b^4 swings back to its normal position, it strikes the end of the shaft b^5 , which releases the trip mechanism, thereby operating the main valve of the machine, which moves the revolving drum a^5 into its reverse position, Fig. 8, which brings the chamber a^4 into the position formerly occupied by the chamber a^3 in Fig. 4, which is directly in line with and in the circuit of the transmission-tube a , so that the carrier A is carried along with the current of air into the transmission-tube. The chamber a^3 now occupies, Fig. 8, the position formerly occupied by the chamber a^4 , as shown in Fig. 4, and is ready to receive another carrier for transmission. When the hammer-weight b^4 in Fig. 6 strikes the rod b^5 , it moves the shoulder b^7 away from the latch b^8 , which swings on the pin c^1 . This latch is held in position by the springs c and pins c^2 . When the shoulder b^7 is disengaged from the latch b^8 , it unlocks the bar d^4 , so that the spring d^6 can throw it into the opposite position, providing the locking-trip c^4 is not engaged with the pin d . The spring d^6 swings at d^7 on the shaft b and is put under tension by the tappet d^8 , the point e' pressing against the spring d^6 when the revolving drum is in position, Fig. 4, and the point e pressing against the opposite side of the spring d^6 , controlling the tension in the opposite direction when the revolving drum is in the reverse position, Fig. 8. When the bar d^4 is thrown into its opposite position, Fig. 10, by the spring d^6 , the rocker-arm e^4 , pivoted at e^5 and connecting the bar d^4 with the piston-rod e^6 of the piston-valve E, having the pistons E' E^2 , Fig. 5, is moved into its reverse position, Fig. 10, and the piston-rod e^6 is turned moved into the reverse position, which reverses the valve E from the position shown in Fig. 5 to that shown in Fig. 7 and opens the port g^2 to supply air-pressure entering through the supply-port g^4 to the cylinder a^9 , so that the piston a^8 is moved to its reverse position (shown

in Fig. 7) and moves the revolving drum a^5 from the position shown in Fig. 4 to that shown in Fig. 8. During the movement of the piston a^8 the air ahead of it escapes through the port g^3 to the exhaust-port g^6 . As the carrier passes through the transmission-tube a , Fig. 6, it operates the locking device which disengages the pin d from the latch c^4 , so that the machine may operate to despatch the next carrier. The vanes f f' are normally balanced, the inside being connected with the transmission-tube a by the port e^9 and the outside by the pipe f^9 , which enters the transmission-tube a at the point e^8 some distance away from the sending-terminal, as before explained. The carrier after leaving the transmitting-terminal is for a very short space of time between the port e^9 and the point e^8 in the transmission-tube a . While the carrier is between these two points the pressure, which is greater back of the carrier than in front of it, is also greater inside the vanes f f' than outside. On account of this greater pressure on the inside the vanes f f' are forced apart against the sides of the vane-case g . Outside the vane-case g and to the spindle upon which the vane f is secured is rigidly connected the lever f^2 , so that when the vanes are forced apart said lever f^2 moves the piston f^4 , which is attached to the rod f^3 , against the spring f^8 into its opposite position, thereby allowing the pressure from the transmission-tube a to flow through the pipe f^9 into the pipe e^7 into the cylinder d^2 , thereby forcing the piston d^4 against the spring d^3 into its opposite position, which is shown in Fig. 10. The pin d is rigidly connected to the piston d^4 , so that when said piston moves to its opposite position the pin releases the latch c^4 , unlocking the machine, so that it is ready for another operation. As the carrier passes the point e^8 in the transmission-tube the pressure on each side of the vanes f f' is equalized and said vanes drop back into their normal positions, Fig. 10, and the spring f^8 forces the piston f^4 into its normal position, Fig. 10, which connects the pipe e^7 with the atmosphere through the exhaust f^6 , thereby allowing the pressure on the front side of the piston d^4 to escape. When the piston d^4 is forced into the position shown in Fig. 10 by the pressure from the pipe f^9 , which flows through the pipe e^7 when the vanes are forced apart, the latch c^4 is disengaged from the pin d and is moved from the position shown in Fig. 6 to that shown in Fig. 10 by the spring c^6 . Now when the pressure is released from the front side of the piston d^4 said piston d^4 is held in the position shown in Fig. 10 by the pin d resting against the latch c^4 , thereby leaving the bar d^4 unlocked so far as the latch c^4 is concerned. Fig. 10 shows the position of the parts of the locking mechanism after a carrier has left the sending-terminal and passed the point e^8 in the transmission-tube. When

the next carrier rolls into the revolving drum a^5 , it trips the latch b^8 , Fig. 10, and the spring d^6 throws the arm d^4 to the extreme opposite end of its motion, which is somewhat farther than shown in Fig. 6, so that the latches c^4 and b^8 may pass the pin d and the shoulder b^7 , allowing said pin d and shoulder b^7 to drop in back of them. When the shaft b moves from the position shown in Fig. 10 to that shown in Fig. 6, the tension of the spring d^6 is reversed, and this forces the latches c^4 and b^8 against the pin d and the shoulder b^7 , as shown in Fig. 6.

The movements of the drum a^5 bring the chambers a^3 a^4 alternately into alinement with the main tube a , and the pressure behind the carriers drives them over the grated T a^7 into the transmission-tube a . The carrier passes from the finger b^2 into the chamber a^3 , Fig. 8, and the same operation takes place as before described—that is, briefly, the bar d^4 is released from the position shown in Fig. 10 and under the tension of the spring d^6 moves to the position shown in Fig. 6. This operation moves the piston-rod e^6 downwardly, thereby moving the valve E , with its pistons E' E'' , from the position shown in Fig. 7 to that shown in Fig. 5, so that the air-pressure entering through the port g^4 to the valve E passes down the port g^3 into the cylinder a^9 and moves the piston a^8 from the position shown in Fig. 7 to that shown in Fig. 5. This operation brings the chamber a^9 , with its carrier, from the position shown in Fig. 8 to that shown in Fig. 4. During this movement of the piston a^8 the air ahead of it escapes through the port g^2 and out through the escape-port g^5 .

To the air-supply port g^4 there is connected the air-supply pipe g^7 , provided with a suitable controlling-valve g^8 . The exhaust to the ports g^5 g^6 passes out through the port G , Fig. 9, to which is connected a suitable exhaust G' , provided with a suitable controlling-valve G^2 .

I do not limit myself to the arrangement and construction shown, as the same may be varied without departing from the spirit of my invention.

Having thus described the nature of my invention and set forth a construction embodying the same, what I claim as new, and desire to secure by Letters Patent of the United States, is—

1. In a pneumatic-despatch apparatus, a main transmission-tube, a sender for the carriers consisting of two chambers, a source of compressed air, mechanism operated by compressed air from said source for moving one of said chambers into alinement with the transmission-tube for transmitting a carrier, a valve controlling the supply of compressed air for operating said mechanism, and mechanism operated by the carrier entering said sender for controlling said valve.

2. In a pneumatic-despatch apparatus, a main transmission-tube, a sender for the carriers consisting of two chambers, a source of

compressed air, mechanism operated by compressed air from said source for moving one of said chambers into alinement with the transmission-tube for transmitting a carrier, a valve controlling the supply of compressed air for 70 operating said mechanism, and yielding mechanism operated by the carrier entering said sender for controlling said valve.

3. In a pneumatic-despatch apparatus, a main transmission-tube, a sender for the carriers consisting of two chambers, a source of compressed air, a cylinder, a piston located in said cylinder and operated by compressed air from said source for moving one of said chambers into alinement with the transmission-tube 75 for transmitting a carrier, a valve controlling the flow of compressed air to the cylinder for operating said valve in opposite directions, mechanism for shifting said valve to direct the compressed air to one side or the other of the 80 piston, and mechanism operated by the carrier entering the sender for controlling said valve.

4. In a pneumatic-despatch apparatus, a main transmission-tube, a sender for the carriers consisting of two chambers, a source of 90 compressed air, a cylinder, a piston located in said cylinder and operated by compressed air from said source for moving one of said chambers into alinement with the transmission-tube for transmitting a carrier, a valve controlling 95 the flow of compressed air to the cylinder for operating said valve in opposite directions, mechanism for shifting said valve to direct the compressed air to one side or the other of the piston, and yielding mechanism operated by the carrier entering the sender for controlling said valve.

5. In a pneumatic-despatch apparatus, a main transmission-tube, a sender for the carriers consisting of receiving-chambers, a 105 source of compressed air, mechanism operated by compressed air from said source for moving one of said receiving-chambers into alinement with the transmission-tube for transmitting a carrier, a valve for controlling the supply of compressed air for operating said mechanism, mechanism for operating said valve and normally locked against movement, and mechanism operated by the carrier entering the sender for controlling the movements of said valve. 110

6. In a pneumatic-despatch apparatus, a main transmission-tube, a sender for the carriers consisting of receiving-chambers, a source of compressed air, mechanism operated by compressed air from said source for moving one of said receiving-chambers into alinement with the transmission-tube for transmitting a carrier, a valve for controlling the supply of compressed air for operating said mechanism, mechanism for operating said valve 120 and normally locked against movement, and yielding mechanism operated by the carrier entering the sender for controlling the movements of said valve. 125

7. In a pneumatic-despatch apparatus, a 130

- main transmission-tube, a sender for the carriers consisting of receiving-chambers, a source of compressed air, mechanism operated by compressed air from said source for moving one of said receiving-chambers into alignment with the transmission-tube for transmitting a carrier, a valve for controlling the supply of compressed air for operating said mechanism, mechanism for operating said valve and normally locked against movement, and mechanism operated by the carrier entering the sender for operating said locked mechanism and controlling the movements of said valve.
- 15 8. In a pneumatic-despatch apparatus, a main transmission-tube, a sender for the carriers consisting of receiving-chambers, a source of compressed air, mechanism operated by compressed air from said source for moving one of said receiving-chambers into alignment with the transmission-tube for transmitting a carrier, a valve for controlling the supply of compressed air for operating said mechanism, mechanism for operating said valve and normally locked against movement, and yielding mechanism operated by the carrier entering the sender for operating said locked mechanism and controlling the movements of said valve.
- 20 9. In a pneumatic-despatch apparatus, a main transmission-tube, a sender for the carriers consisting of receiving-chambers, a source of compressed air, mechanism operated by compressed air from said source for moving one of said receiving-chambers into alignment with the transmission-tube for transmitting a carrier, a valve for controlling the supply of compressed air for operating said mechanism, mechanism for operating said valve and normally locked against movement, and yielding mechanism operated by the carrier entering the sender for operating said locked mechanism and controlling the movements of said valve.
- 25 10. In a pneumatic-despatch apparatus, a main transmission-tube, a sender for the carriers consisting of receiving-chambers, a source of compressed air, mechanism operated by compressed air from said source for moving one of said receiving-chambers into alignment with the transmission-tube for transmitting a carrier, a valve for controlling the supply of compressed air for operating said mechanism, mechanism for operating said valve and normally locked against movement, and yielding mechanism operated by the carrier entering the sender for operating said locked mechanism and controlling the movements of said valve.
- 30 11. In a pneumatic-despatch apparatus, a main transmission-tube, a sender for the carriers consisting of receiving-chambers, a source of compressed air, mechanism operated by compressed air from said source for moving one of said receiving-chambers into alignment with the transmission-tube for transmitting a carrier, a valve for controlling the supply of compressed air for operating said mechanism,

mechanism for operating said valve and normally locked against movement, mechanism 40 operated by the carrier entering the sender for operating said locked mechanism and controlling the movements of said valve, and a supplemental locking device for said valve-operating mechanism adapted to be operated by 45 air compressed ahead of the carrier for moving said locking device from engagement with said valve-operating mechanism.

10. In a pneumatic-despatch apparatus, a main transmission-tube, a sender for the carriers consisting of receiving-chambers, a source of compressed air, mechanism operated by compressed air from said source for moving one of said receiving-chambers into alignment with the transmission-tube for transmitting a 55 carrier, a valve for controlling the supply of compressed air for operating said mechanism, mechanism for operating said valve and normally locked against movement, yielding mechanism operated by the carrier entering 60 the sender for operating said locked mechanism and controlling the movements of said valve, and a supplemental locking device for said valve-operating mechanism adapted to be operated by air compressed ahead of the carrier for moving said locking device from engagement with said valve-operating mechanism.

In testimony whereof I have signed my name to this specification, in the presence of two subscribing witnesses, this 21st day of December, 70 A. D. 1903.

CHARLES F. STODDARD.
